(57) **CLAIM**

The ornamental design for a vaporizer cartridge container, as shown and described.

DESCRIPTION

FIG. 1 is a top, front, and right side perspective view of a first-embodiment of a vaporizer cartridge container of our design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and

FIG. 8 is an exploded perspective view of the vaporizer cartridge container in an open position.

FIG. 9 is a top, front, and right side perspective view of a second embodiment of a vaporizer cartridge container of our design;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof; and,

FIG. 16 is an exploded perspective view of the vaporizer cartridge container in an open position.

In FIGS. 1–15, the dash-dash broken lines illustrate portions of the vaporizer cartridge container that form no part of the claimed design. In FIG. 16, the dash-dash broken lines illustrate environment that forms no part of the claimed design.

1 Claim, 10 Drawing Sheets
